[57] CLAIM

The ornamental design for an electronic scale, substantially as shown and described.

DESCRIPTION

FIG. 1 is a top and right front perspective view of an electronic scale showing my new design;

FIG. 2 is a front elevational view thereof;

FIG. 3 is a rear elevational view thereof;

FIG. 4 is a left side elevational view thereof;

FIG. 5 is a bottom perspective view thereof;

FIG. 6 is a top and right-front perspective view thereof in partially folded position;

FIG. 7 is a top plan view thereof in a fully folded position;

FIG. 8 is a front elevational view of FIG. 7.
